UNITED STATES PATENT OFFICE

CARL A. BROWN AND ANDREAS C. NIELSEN, OF CLEVELAND, OHIO, ASSIGNORS TO
GENERAL ELECTRIC COMPANY, A CORPORATION OF NEW YORK

GAS BURNER

Application filed July 23, 1923. Serial No. 653,084.

Our invention relates to gas burners and is adapted for use with natural or artificial gas. The object of our invention is to provide a burner from which a uniform intense heat is secured. We secure this result by providing means for securing a very thorough mixture of the gas with air and for securing a very uniform pressure. Our invention is adapted to glass working, particularly to the various operations on bulbs and tubing entering into the manufacture of incandescent lamps and similar devices. Further advantages and features of our invention will appear from the description which follows of species thereof and from the accompanying drawing in which Fig. 1 is a front elevation partially broken away; Fig. 2 is a horizontal section; Fig. 3 is a side elevation partially broken away and in section; Fig. 4 is a partial perspective of the fire plate; and Fig. 5 is a partial front elevation of a modification of the burner adapted for artificial gas.

In the drawing 10 is a casing or burner body within which is located a distributing chamber or inner tube 11 which rests on a shoulder formed at the junction of the casing 10 with a bottom chamber 12 to which is connected the intake pipe 13. The casing 10 may have an extension 10' by means of which the burner may be adjustably supported. The tube 11 has, along the rear thereof, distributing orifices 14 which are preferably arranged in a double row and staggered and communicate with the outer distributing chamber 15 formed between the inner tube and the casing 10. Diametrically opposite to the rows of orifices 14, the casing 10 has an external slot 16 extending substantially its entire length and communicating therewith are larger high pressure orifices 17, preferably arranged in a double row and staggered, and on each side of said double row is a row of smaller low pressure orifices 18, the latter also being staggered. A fire plate 19 is mounted in said slot and is T-shaped in horizontal section. It contains a double row of staggered high pressure fire orifices 20 which are aligned with orifices 17. The fireplate forms with the bottom of slot 16 a pair of lateral low pressure distributing chambers 21 with

which communicate the low pressure orifices 18. Each of the wings of the fireplate has a row of low pressure fire orifices or slots 22 which communicate with the low pressure distributing chambers 21 and allow the escape 55 of the low pressure gas which is ignited.

A burner of the above described construction alone may be used to advantage for artificial gas. However for natural gas it has been found desirable to provide a means for further breaking up the current of gas issuing from the slots 22. Members such as strips of wire gauze 23 having numerous small apertures therethrough and arranged so that each strip covers a row of slots 22 have been found 65 to be particularly serviceable for this purpose. These are removably held by plates 24 and bent so as to cover the said slots.

In operation gas and air in proper proportions and suitable pressure enter chamber 12 70 and fill tube 11. The mixture then flows through double row orifices 14 into the outer distributing chamber 15. The mixture issuing from the orifices 14 strikes against the wall of the casing 10 and is deflected around 75 the chamber 15 and out through high pressure orifices 17 and low pressure orifices 18. This arrangement insures a uniformity of pressure in the gas mixture issuing from the several orifices. It also serves to improve the 80 thoroughness of mixture of the gas constituents. The result is that a more uniform heat is secured than from burners otherwise constructed. The low pressure flame produced from the mixture flowing from the slots 85 serves to prevent the blowing out of the high pressure flame. The slot construction is particularly effective since it enables the low pressure flame to be brought very close to the high pressure orifice. 90

The provision of the supplementary means, specifically the gauze covering, for breaking up the gas mixture issuing from the low pressure orifices permits the use of natural gas. Heretofore considerable difficulty has been 95 experienced in maintaining a high pressure concentrated natural gas flame such as is used in glass working and particularly for operations on glass tubing which enter into incandescent lamp manufacture. Our invention 100

overcomes this difficulty. The gauze being spaced from the orifice causes the flame to form between the gauze and the orifice which spreads out and this is particularly effective in maintaining the main fire.

What we claim as new and desire to secure by Letters Patent of the United States, is:

1. A gas burner comprising a casing, an inner tube spaced from said casing to form a chamber, said tube having orifices on one side thereof communicating with said chamber and said casing having longitudinal rows of orifices disposed on the side thereof opposite to that of said inner tube orifices, and a fire-plate having a body portion provided with a row of orifices communicating with a row of those in said casing and a wing portion spaced from said casing opposite a row of said casing orifices to form a distributing chamber and having a row of orifices therein each disposed adjacent to one of the said body portion orifices.

2. A gas burner comprising a casing, an inner tube spaced from said casing to form a chamber, said tube having orifices on one side thereof communicating with said chamber and said casing having longitudinal rows of orifices disposed on the side thereof opposite to that of said inner tube orifices, and a fire-plate having a body portion provided with a row of orifices communicating with a row of those in said casing and a wing portion spaced from said casing opposite a row of said casing orifices to form a distributing chamber and having a row of slot-shaped orifices therein each disposed adjacent to one of the said body portion orifices.

3. A gas burner comprising a casing, an inner tube spaced from said casing to form a chamber, said tube having orifices on one side thereof communicating with said chamber and said casing having longitudinal rows of orifices disposed on the side thereof opposite to that of said inner tube orifices, and a fire-plate having a body portion provided with a row of orifices communicating with a row of those in said casing and wing portions each spaced from said casing opposite a row of said casing orifices to form a distributing chamber and having a row of orifices therein each disposed adjacent to one of the said body portion orifices.

In witness whereof, we have hereunto set our hands this 19th day of July, 1923.

55   CARL A. BROWN.
                         ANDREAS C. NIELSEN.
